REFRIGERATED DISPLAY CASE

Frederick D. Chapman, Chicago, and Kim Yamasaki,
Lombard, Ill., assignors to Hussmann Refrigerator Co.,
St. Louis, Mo., a corporation of Delaware

Filed May 15, 1959, Ser. No. 55,922

Term of patent 14 years

(Cl. D80—11)

FIG.1

FIG.4

FIG. 2

FIG. 3

Fig. 1 is a front perspective view of a refrigerated display case embodying our design,

Fig. 2 is a front elevational view of the refrigerated display case,

Fig. 3 is a fragmentary side elevational view taken from the side opposite to that shown in Fig. 1, and

Fig. 4 is a fragmentary top plan view of the refrigerated display case.

The dominant features of the design reside in the portions shown in full lines.

We claim:

The ornamental design for a refrigerated display case, substantially as shown and described.
